LOAD INDICATOR

Edward D. Treanor, Pittsfield, Mass., assignor to General Electric Company, a corporation of New York

Application January 20, 1954, Serial No. 405,141

7 Claims. (Cl. 340—222)

This invention relates to a load indicator, and more particularly, to a load indicator for electrical apparatuses.

A well known type of switch or circuit breaker comprises a pair of circuit breaker contacts and a load indicator or signal mechanism. A bimetallic element, movably responsive to the amount of current drawn by an electrical apparatus to be protected from overloads or the like by said circuit breaker, is operable first to actuate said signal mechanism from a non-indicating condition to an indicating condition upon a predetermined overload level less than a predetermined overload trip level of said circuit breaker contacts, and then to actuate said circuit breaker contacts from a closed position to a tripped open position when the overload trip level of said circuit breaker contacts has been reached. One form of such type of switch or circuit breaker is shown in Patent 2,487,534 issued November 8, 1949 to J. A. Favre, and assigned to the same assignee as the instant application.

When such type of switch or circuit breaker is used to protect an electrical system such as a transformer, it may not always be desirable for the circuit breaker to take the transformer off the line the moment the circuit breaker contacts overload trip level have been reached. For instance, the overload condition may be only transient and not of a serious enough nature to damage the transformer or materially decrease its life expectancy. However, if the transformer is taken off the line, there is an interruption in service during the time required for an operator to go out to the transformer station to reset and close the circuit breaker.

Accordingly, in a circuit breaker adapted to protect an electrical circuit from overloads or the like, said circuit breaker having a movable bimetallic element positioned electrically in series in said electrical circuit, said circuit breaker having a signal mechanism and a pair of circuit breaker contacts positioned electrically in series in said circuit, said bimetallic element operable first to actuate said signal mechanism from a non-indicating condition to an indicating condition upon the occurrence of an overload in said circuit less than a predetermined overload trip level of said circuit breaker contacts, and then operable to actuate said circuit breaker contacts from a closed position to a tripped open position when the overload trip level of said circuit breaker contacts have been reached, it is an object of this invention to provide means wherein when said circuit breaker contacts are actuated to said tripped open position said circuit will remain electrically closed and a shunt path will be provided in said circuit around said bimetallic element to protect said bimetallic element from overcurrents in said circuit whereby said circuit breaker is converted into a load indicator at a minimum cost.

It is a further object of this invention to provide an overload indicator having an actuating bimetallic element adapted to be disposed in an electrical circuit, and shunt means operative substantially instantaneously subsequent to actuation of said overload indicator by said bimetallic element whereby said bimetallic element is substantially protected from an overcurrent in said circuit, said shunt means providing a shunt path around said bimetallic element whereby said overcurrent will substantially bypass said bimetallic element.

In a circuit breaker adapted to protect an electrical circuit from overcurrents and the like, said circuit breaker having a movable bimetallic element positioned electrically in series in said circuit, said circuit breaker hav-

ing a pair of circuit breaker contacts positioned electrically in series in said circuit and a signal mechanism, said bimetallic element adapted to actuate said signal means and trip open said circuit breaker contacts, actuation of said signal means preceding tripping open of said circuit breaker contacts, my invention comprises shunt means for automatically shunting said bimetallic element to protect said bimetallic element from overcurrents in said circuit and for automatically electrically closing said circuit upon tripping open of said circuit breaker contacts whereby said circuit breaker is converted into a load indicator at a minimum cost.

My invention further comprises a signal mechanism having a movable bimetallic element positioned electrically in an electrical circuit, said bimetallic element operable to actuate said signal mechanism upon the occurrence of an overcurrent in said circuit, and shunt means for automatically shunting said bimetallic element following actuation of said signal mechanism by said bimetallic element whereby said bimetallic element is substantially protected from said overcurrent.

The features of my invention which I believe to be novel are set forth with particularity in the appended claims. My invention itself, however, both as to its organization and method of operation, together with further objects and advantages thereof, may best be understood by reference to the following description taken in connection with the accompanying drawing.

In the drawing, Fig. 1 is a partly broken away perspective view of an embodiment of my invention. Fig. 2 is a diagrammatic electrical circuit illustration of my invention. Like reference numerals will be used in Figs. 1 and 2 to designate identical parts.

Referring now to the drawing, and more particularly, to Fig. 1, shown therein is a switch or circuit breaker in its tripped opened position. The switch or circuit breaker comprises a pair of bimetallic elements 10, only one of which is shown in Fig. 1, a pair of stationary contacts 11, and a pair of movable contacts 12. Each bimetallic element 10 comprises a pair of elongated bimetallic members 13 and 14 disposed generally parallel with respect to each other and electrically disconnected from each other except at their rear ends. At said rear ends the pair of elongated bimetallic members 13 and 14 are electrically interconnected by a finger 15.

The bimetallic elements 10 are immovably mounted at their forward ends in an insulating material base 16, and said rear ends or fingers 15 are floatingly mounted whereby said rear ends or fingers 15 are free for upward deflection upon the flow of an electrical current through parts 13, 15, and 14. The stationary contacts 11 are electrically connected to the bimetallic members 14. The left-hand bimetallic element 10 and the left-hand contacts 11 and 12 are disposed electrically in series in an electrical circuit to be protected by the circuit breaker or switch. For instance, one terminal of the electrical circuit to be protected is connected to the left-hand bimetallic member 13 at left-hand tab 17 and another terminal of said electrical circuit is connected to the left-hand movable contact 12 at left-hand tab 18 electrically in contact with the left-hand movable contact 12. With the left-hand contacts 11 and 12 closed, electrical current will flow from tab 17 to bimetallic member 13, finger 15, bimetallic member 14, stationary contact 11, movable contact 12, and thence to tab 18. As will be more clear hereinafter, upon the occurrence of an overload or overcurrent of a predetermined level in said electrical circuit the end 15 of bimetallic element 10 will be deflected upwardly and result in actuation of a signal means, to be described hereinafter, from a non-indicating condition to an indicating condition. Also, if said overload or overcurrent reaches a slightly higher predetermined level, the finger 15 of bimetallic element 10 will be deflected upwardly still further which will result in tripping open of the circuit breaker contacts 11 and 12.

Referring now also to Fig. 2, the hereinbefore mentioned signal or indicating mechanism comprises a warning light circuit having a stationary warning light contact 20, a movable warning light contact 21, and a warning light 22 shown only in Fig. 2. In Fig. 2 the warning

light contacts 20 and 21 are shown in their disengaged position whereby the warning light 22 is off, and in Fig. 1 the warning light contacts 20 and 21 are illustrated in their engaged position wherein the warning light circuit is closed and the warning light 22 is on. Movable warning light contact 21 is a generally horizontally disposed rod-like member connected to a generally vertically disposed elongated member 23 as by welding or the like. Elongated member 23 is disposed substantially normal to the rod-like movable warning light contact 21. Disposed substantially parallel to the rod-like movable warning light contact 21 adjacent the lower end of elongated member 23 is a latching plate 24. Latching plate 24 is carried by a pivotally mounted and horizontally disposed member 25 which is continuously biased clockwise by a not shown spring. The elongated member 23 is continuously urged downwardly and rearwardly by an inclined spring 26.

As will be seen from Fig. 2, when the warning light 22 is off the lower end of the elongated member 23 rests upon the upper surface of the latching plate 24 whereby the movable warning light contact 21 is raised from electrical contact with the stationary warning light contact 20. The inclined spring 26 retains the elongated member 23 from sliding off the upper surface of latching plate 24 and falling below the latching plate 24. As will be clearly seen from Fig. 1, the free end 15 of bimetallic element 10 has a contact projection 27 thereon adapted to engage an integral projection 28 of the member 25. Accordingly, when an overcurrent of sufficient magnitude occurs and the bimetallic element 10 is deflected upwardly, the member 25 with its latching plate 24 will be pivoted counterclockwise whereby the latching plate 24 will be removed from the downward path of movement of the elongated member 23. Thereafter the inclined spring 26 is free to pull the elongated member 23 downwardly below the latching plate 24 to place the movable warning light contact 21 in engagement with the stationary warning light contact 20, as illustrated in Fig. 1.

As will be seen more clearly from Fig. 2, the pair of movable circuit breaker contacts 12 are carried by switch arms 30 pivotally mounted at their rear ends. When the contacts 11 and 12 are engaged with each other, a not shown latching mechanism, fully described in the heretofore mentioned Patent 2,487,534, has a latching tooth thereof in engagement with the upper surface of latching plate 24. However, a greater portion of said latching tooth is in engagement with the latching plate 24 than there is of the lower end of elongated member 23 in engagement with latching plate 24. Accordingly, as the latching plate 24 is pivoted counterclockwise the lower end of elongated member 23 will be released first to close the warning light contacts 20 and 21. If the overload condition in the electrical circuit to be protected by the circuit breaker or switch persists and reaches a still higher level, the ends 15 of the bimetallic elements 10 will be deflected upwardly still further after which the latching plate 24 will be pivoted counterclockwise sufficiently to release the previously mentioned latching tooth. Thereafter, the switch arms 30 are free to be snapped upwardly by a spring 31, see Fig. 1, whereby the movable circuit breaker contacts 12 are disengaged from the stationary circuit breaker contacts 11 to interrupt or open the electrical circuit to be protected.

Opening of the electrical circuit to be protected by the switch or circuit breaker is not always desirable. For instance, in Fig. 2 the circuit breaker or switch is illustrated as being adapted to protect an electrical apparatus, such as a transformer, from overcurrents or overloads in the secondary windings 32 of said transformer, the neutral point of winding 32 being grounded as is well known in the art. Many overcurrents or overloads in electrical apparatuses such as transformers are only of an instantaneous or transient nature and not severe enough to cause damage to said transformers or decrease their life expectancies. In such a situation it may be more economical to keep the transformer on the line during said instantaneous or transient overcurrent or overload rather than for the transformer to be taken off the line and thereby have a resulting discontinuity in electrical service until an operator can get out to the transformer station to reset and close the switch or circuit breaker and reestablish electrical service. Accordingly, in my invention I provide means whereby though the signal mechanism is actuated to its indicating condition and though the circuit breaker

contacts are mechanically tripped open to their electrical circuit open position the electrical circuit to be protected is electrically closed. That is, the circuit breaker function of the switch or circuit breaker is eliminated whereby the circuit breaker functions only as a load indicator.

As seen in Figs. 1 and 2 interconnecting the disengagable contacts 11 and 12 are flexible conductors 35. Accordingly, when the circuit breaker contacts 11 and 12 are mechanically tripped open the electrical apparatus to be protected is not taken off the line. However, since the electrical circuit of the electrical apparatus to be protected is not interrupted upon the occurrence of an overcurrent or overload in said electrical circuit, the overcurrent will continue to flow through the bimetallic elements 10. Repeated subjection of the bimetallic elements 10 to overcurrents rapidly decreases their life expectancy. Accordingly, in my invention I provide shunt means whereby after the switch or circuit breaker contacts have been mechanically tripped open the overcurrent will substantially bypass the bimetallic elements 10 thereby protecting them from rapid deterioration.

Said shunt means comprises two generally U-shaped members 36. As seen most clearly from Fig. 1, the generally U-shaped members 36 are disposed so that their base portions extend in a generally vertical direction. A leg of the U-shaped members 36 is electrically connected to the bimetallic members 13 and the other leg of the U-shaped members 36 overlies the movable circuit breaker contacts 12. When the movable circuit breaker contacts 12 are engaged with the stationary circuit breaker contacts 11, the upper leg portions of generally U-shaped members 36 are vertically superposed with respect to the tabs 18 and spaced therefrom. However, when the movable circuit breaker contacts 12 are tripped open, the tabs 18 will be raised upwardly along with the contacts 12 and be placed in electrical contact with the upper leg portions of the U-shaped members 36. Accordingly, a shunt circuit is provided around the bimetallic elements 10 after the circuit breaker contacts 12 have tripped open whereby the overcurrent in the electrical circuit to be protected can substantially bypass the bimetallic elements 10. If the flexible conductors 35 interconnecting the contacts 11 and 12 were not present the U-shaped members 36 alone would keep the electrical circuit to be protected closed despite the fact that the circuit breaker contacts 12 have been disengaged from the contacts 11. However, from the instant after which the contacts 12 leave the contacts 11 until the instant during which the tabs 18 come in electrical contact with the upper leg portions of the U-shaped members 36 an instantaneous discontinuity in electrical service is introduced. Accordingly, in my invention I prefer to also utilize the flexible conductors 35 so that there is no discontinuity in service whatsoever while the circuit breaker contacts are being mechanically disengaged. Furthermore, without the flexible shunt conductors 35 the instant the contacts 12 become disengaged from the contacts 11 electrical arcing would occur therebetween. Electrical arcing between the contacts 11 and 12 may tend to deteriorate them. However, if the contacts 11 and 12 are interconnected by the flexible shunt conductors 35, no electrical arcing can occur between the contacts 11 and 12 thereby tending to preserve them. After contacts 12 are tripped open shunt elements 36 also shunt the contacts 11, 12 and the flexible conductors 35.

Thus, it will now be apparent that I have provided a load indicator at a minimum cost by uniquely eliminating the circuit interrupting function of a well known type of circuit breaker having a signal mechanism; the load indicator comprising a signal mechanism and a bimetallic element adapted to actuate said signal mechanism from a non-indicating condition to an indicating condition with shunt means automatically operable to substantially protect said bimetallic element from overcurrents or the like.

While there has been shown and described a particular embodiment of the invention, it will be obvious to those skilled in the art that changes and modifications can be made without departing from the invention, and that it is intended by the appended claims to cover all such changes and modifications as fall within the true spirit and scope of the invention.

What I claim as new and desire to secure by Letters Patent of the United States is:

1. A load indicator comprising a signal mechanism adapted to be actuated from a non-indicating condition to an indicating condition and a bimetallic element adapt-

ed to be electrically positioned in an electrical circuit, said bimetallic element movably responsive to overcurrents in said circuit to actuate said signal mechanism, shunt means automatically operable substantially instantaneously subsequent to actuation of said signal mechanism to said indicating condition for shunting said bimetallic element whereby said overcurrents will substantially bypass said bimetallic element.

2. A load indicator comprising an indicating mechanism adapted to be actuated from a non-indicating position to an indicating position and a bimetallic element positioned electrically in series in an electrical circuit, said bimetallic element movably responsive to a predetermined electrical load level in said circuit to actuate said indicating mechanism to said indicating position, a shunt automatically operable substantially instantaneously subsequent to actuation of said indicating mechanism to said indicating condition shunting said bimetallic element to protect said bimetallic element from substantial overcurrents in said circuit.

3. A load indicator comprising an electric light circuit having an electric light bulb therein and a pair of engageable and disengageable contacts therein adapted respectively to close and open said electric light circuit to respectively put said electric light bulb on and off, said load indicator having a bimetallic element adapted to be positioned electrically in series in another electric circuit, said bimetallic element movably responsive to a predetermined load in said another circuit to cause engagement of said contacts, and shunt means operable subsequent to engagement of said contacts to provide a shunt path in said another circuit around said bimetallic element.

4. In a switch adapted to protect an electrical circuit from a substantial overcurrent, said switch having a movable bimetallic element positioned electrically in series in said circuit movably responsive to a substantial overcurrent in said circuit, said switch having a signal mechanism and a pair of closed contacts positioned electrically in series in said circuit, said bimetallic element adapted to first actuate said signal mechanism, and then to open said contacts in response to a substantial overcurrent in said circuit, means automatically electrically shunting said bimetallic element to protect said bimetallic element from a substantial overcurrent in said circuit and for automatically electrically closing said circuit substantially instantaneously subsequent to opening of said contacts whereby said switch operates only as an overcurrent indicator.

5. In a circuit breaker adapted to protect an electrical circuit, said circuit breaker having a movable bimetallic element adapted to be positioned electrically in series in said circuit and movably responsive to overcurrents in said circuit, said circuit breaker having an indicating mechanism operable in response to movement of said bimetallic element, said circuit breaker having a pair of closed cir-

cuit breaker contacts positioned electrically in series in said circuit disengageable in response to movement of said bimetallic element, said bimetallic element adapted to actuate said indicating mechanism prior to disengagement of said contacts, shunt means automatically operable subsequent to disengagement of said contacts whereby substantial overcurrents in said circuit will substantially bypass said bimetallic element and said contacts substantially instantaneously subsequent to disengagement of said contacts for retaining said electrical circuit closed whereby said circuit breaker will operate only as an overcurrent indicator.

6. A load indicator having a movable bimetallic element disposed electrically in series in an electrical circuit movably responsive to overcurrents in said circuit, said load indicator having a signal mechanism actuatable in response to initial movement of said bimetallic element, said load indicator having a pair of closed contacts disposed electrically in series in said circuit adapted to be mechanically opened upon further movement of said bimetallic element, flexible conductor means electrically interconnecting said contacts whereby said circuit is electrically closed even though said contacts are mechanically opened, and shunt means operable subsequent to opening of said contacts whereby overcurrents in said circuit can substantially bypass said bimetallic element substantially instantaneously subsequent to mechanical opening of said contacts.

7. A load indicator for an electrical apparatus, said load indicator having a movable bimetallic element disposed electrically in an electrical circuit portion of said electrical apparatus and movably responsive to an overcurrent in said circuit portion, said load indicator having an indicating mechanism actuatable in response to movement of said bimetallic element upon passage of an overcurrent therethrough, said load indicator having a pair of closed contacts disposed electrically in said circuit portion, said contacts disengageable from each other in response to movement of said bimetallic element upon passage of an overcurrent therethrough, said bimetallic element and contacts disposed electrically in series in said circuit portion, said indicating mechanism actuatable prior to disengagement of said contacts, a flexible conductor interconnecting said contacts for prohibiting electrical arcing therebetween during disengagement thereof, and a shunt shunting said bimetallic element, contacts and flexible conductor substantially instantaneously subsequent to disengagement of said contacts whereby an overcurrent in said circuit portion will substantially bypass said bimetallic element, flexible conductor, and contacts, said flexible conductor and shunt maintaining said circuit portion closed despite disengagement of said contacts.
